WILLETT CORNWELL AND ELMIRA CORNWELL, OF ROCHESTER, MINNESOTA.
BEST AVAILABLE COPY

Design No. 3,898, dated March 15, 1870.

DESIGN FOR A PATTERN OR CHART FOR APPLYING MEASUREMENTS AND LAYING OUT DRESS-WAISTS.

The Schedule referred to in these Letters Patent and making part of the same

To all whom it may concern:

Be it known that we, WILLETT CORNWELL and ELMIRA CORNWELL, of Rochester, in the county of Olmsted, and State of Minnesota, have invented certain new and useful Improvements in Design for a Chart for Cutting Ladies' Dresses; and we do hereby declare that the following is a full, clear, and exact description thereof, reference being had to the accompanying drawings making part of this specification, and to the letters of reference marked thereon, like letters indicating like parts wherever they occur.

To enable others skilled in the art to construct and use our invention, we will proceed to describe it.

Our invention consists in a novel design for a chart for applying measurements and laying out dress-waists, whereby ordinary persons are enabled to measure, lay out, and cut dresses to fit any one, using only the chart and the instructions accompanying the same.

The design consists of two parts, one for the front, and the other for the back, each having printed or marked thereon a series of scales, curves, and angles, as represented in the drawings, for laying out the waist in accordance with certain measurements to be taken of the person, and then applied to the various scales, as hereinafter described.

Figure 1 represents the front chart, and

Figure 2, the rear or back chart.

We make our chart of paper or pasteboard, with the scales, figures, and marks printed thereon, according to the design illustrated in the drawings.

The manner of using our chart is as follows:

With a tape-measure, divided into inches and parts of inches, take and set down on paper for reference—

First, the bust-measure about the person close under the arms. The measure should be over the fullest part of the bust, and be taken loosely.

Second, the waist-measure, snug around the body, about eight inches below the arms.

Third, the length of waist, from immediately under the arm (at side of the person) down to the bottom edge of the proposed dress-waist.

Fourth, the shoulder-measure, from the top of the neck-band (of the proposed dress) along the top of the shoulder to the hollow or bend of the collar-bone, just behind that bone and about an inch from the outer end of it. To take the measure properly requires some care, as the points of measurement are necessarily indefinite, and vary considerably with round, square, or slanting shoulders. It is taken most readily while standing behind the person measured. The most common length of this measure is about three and a half inches.

Fifth, the taper measure is found by subtracting the waist-measure from the bust-measure.

To cut front of waist for body of medium size, take one yard of three-quarter yard wide dress-lining, fold it equally together, and fasten with pins, and lay the cloth on the table with the cut ends toward you, and so that the selvage will be at your right and left sides. Then take the front chart, fig. 1, and

First, place it on the cloth with the longest straight edge about one and a quarter inch to the right, and parallel to the left selvage-edge of cloth, and with the "neck size" end about half inch down from the doubled or cut edges of the cloth. The figures and letters on the chart will now be right side up in reference to you.

Second, with one hand hold the chart firm, and with a pencil mark the cloth along the whole left-hand straight edge of the chart.

Third, dot the cloth about the "neck size" through the five holes in the curved line, in which is the number of your "bust-measure."

Fourth, dot through the holes at the number indicating your "bust-measure" in the scales A, B, C, D, and E.

Fifth, dot through the holes at the right, and also at the left of the number indicating your "bust-measure" in scale F F.

Sixth, in the column of figures in the left of scale G, find the number indicating your "waist-measure," and in a straight line therefrom to the right, find the number indicating your bust-measure, and dot through the hole at the top and the one at the bottom of the column, in which is this last number.

Seventh, remove the chart from the cloth, and draw a curved line for the "neck size" through the first five dots made, and another line from the dot made through the scale A, through the dot through the scale B, C, and D, to the dot made through the scale E, moving in the direction of the line on the chart.

Eighth, draw a straight line through the dots made through scale G, continuing the line one inch or more above for a small person, and an inch or more below for a large person.

Ninth, take the back chart, fig. 2, and place the point J at the dot made through scale E. Swing the chart around to the left, until the last line made on the cloth (through dots in scale G) is intersected by the scale edge at the number indicating "length of waist." Then draw a line along the scale edge from dot made through scale E (point J being at this dot) down to the intersected line.

Tenth, remove "back chart" and replace "front chart," with the straight left-hand edge at the line

where it was before. Then move the chart up or down, keeping the left edge on a line until the bottom "sloping edge," near the lower right hand, comes to the line end of the last line drawn, at its intersection with the line drawn through the dots made through the scale G. Then from that point of intersection draw a line to the left along the entire bottom of the chart.

Eleventh, dot through the hole at H; also through the three holes in scale H, at the bottom of the three respective columns, in each of which is the number indicating the "taper measure," as found by subtracting the waist-measure from the bust-measure.

Twelfth, find a point on the upper edge of the chart in the scale at the left of I, indicated by the figures there corresponding with the number of the "shoulder-measure," then moving the chart, so that this point on the edge of the chart will be at star at the end of line in which neck-measure dots are made, and swing the bottom of the chart to left (or right) until the upper edge shall be at the dot made through scale A. Then mark along the upper edge of the chart from the point to the dot mentioned.

Thirteenth, remove front chart and take back chart. Place point J at the left dot made through the scale F F, and swing the chart to the left, so that the scale edge shall come to the dot made through hole at H. Then mark along scale edge from point J to dot. Now turn chart over to right, reverse side up, and with point J at same dot as before. Swing chart to right until scale edge is at the dot made through scale H, first to the right of dot at H, then mark along scale-edge of chart from point J to dot. Move chart bodily to the right (reverse side still up) until point J is at the dot made through the right of scale F F, and the scale edge is at the dot made through scale H; third, to the right of dot at H, then mark along scale edge of chart from point J to dot. Now turn chart over to left, (face side up,) and with point J still at the same dot as last before. Swing chart to left until scale edge is at dot made through H, second to the right of dot at H, then mark along scale edge of chart from point J to dot.

Fourteenth, lay chart aside. With shears cut from lower left-hand corner through both thicknesses of cloth toward the right, on the line across the bottom. Cut to some inch beyond the perpendicular line made through the dots in scale G; then to left parallel to and one inch from line until a little above dot made through scale E, then through dot in E, and on and along the curved line up to and one inch beyond the dot made through scale A; then to the left parallel to and one inch from the line at a point opposite the end of it; then down through the star dot, and on and along the curved neck-line to the last line, and then slanting up about one-quarter inch to the edge of cloth. Break the cloth over or crease it along all lines not cut out, so as to leave an impression on the under cloth to guide you where to sew up the seams.

The one and a quarter inch space allowed at the left edge of cloth is for turning under and lapping purposes.

To cut back of waist, swing the remaining cloth (still doubled and fastened together with pins) around so that the ends that were toward you before will now be away from you, and so that the remaining selvage-edges will be at your left hand. Place the "back chart" on the cloth, with the long straight edge at the left selvage-edges of the cloth, with the upper "neck size" end about one-half inch down from the upper edge of the cloth. The reading now of the chart will be right side up with reference to you.

First, with hand, hold (back) chart firmly. In the scale at neck size find the number indicating your

"bust-measure," and mark through the hole above or below that number.

Second, dot through holes at the number indicating your "bust-measure" in scale A B C.

Third, dot through two holes immediately above and below the numbers indicating your waist-measure in scale D D.

Fourth, move the chart down about one-half inch, until the top edge is at the dot made through the scale at neck size, then draw a line from that dot to the left along the top edge of the chart to the edge of the cloth.

Fifth, place point E of chart at dot made through scale at "neck size," and the long curved edge at the dot made through scale A, and draw a line along edge of chart from point E to dot last mentioned.

Sixth, remove chart. Draw a curved line through dots made through scale A B C, in the direction indicated by line on chart.

Seventh, draw a straight line through the two dots made through the scale D D, extending line an inch or more above and below dots.

Eighth, place point J at the dot made through scale C, swing chart to left until the last line made on the cloth (through holes in scale D D) is intersected by the scale edge of the chart at the number indicating "length of waist;" then draw a line along scale edge from point J down to the intersected line.

Ninth, with long straight edge of chart draw a line from this last point of intersection square out to left to edge of cloth.

Tenth, turn over chart, reverse side up, and place the edge of chart at the printed point G, on the dot on the cloth made through scale B, and swing the chart around, so that the edge marked "back form" will intersect the last line drawn about one-half inch from the left edge of cloth, and draw a line from the dot along edge of chart to point of intersection. The line will curve, as indicated by line on chart.

Eleventh, lay chart aside; with shears cut from lower left-hand corner through both thicknesses of cloth, toward the right on the line across the bottom, out to and one inch beyond the straight line drawn through dots from scale D D, then parallel to and one inch from line up opposite to dot made through scale C, then to left on curved line through dots made through C, B, and A, and one inch beyond A, then parallel to and one inch from line up to and opposite dot made through "neck size," along top line to edge of cloth.

Twelfth, sew together the two back pieces of cloth at the long straight edges; break the cloth over or crease it along all lines not cut out, to leave an impression on the under cloth to guide you where to sew the seams.

Thirteenth, in sewing together the shoulder-seams full the back to the front, the back pattern is about three-eighths of an inch longer on the shoulder than the front pattern. Sew together through the lines those made by the scale edge of the "back chart" the back cloth to the front cloth, two by two. Sew together through the lines made by the scale edge of the back chart from scale F F to H, on the front cloth, two by two.

Having thus described our invention,

What we claim is—

The herein-described design for a pattern or chart, for applying measurements and laying out dress-waists.

WILLETT CORNWELL.
ELMIRA CORNWELL.
